CLAIM

[**] Term: 14 Years

The ornamental design of a covering for magnetic tape
cassette, substantially as shown and described.

[21] Appl. No.: 662,936

DESCRIPTION

[22] Filed: Oct. 19, 1984

FIG. 1 is a rear perspective view of a covering for
magnetic tape cassette showing my new design;
FIG. 2 is a front perspective view thereof; and
FIG. 3 is a rear perspective view thereof attached to a
cassette.
